UNITED STATES PATENT OFFICE.

WILLIAM B. CROWTHER, SR., OF OCEAN BEACH, NEW JERSEY.

CHIMNEY COWL AND VENTILATOR.

SPECIFICATION forming part of Letters Patent No. 357,269, dated February 8, 1867.

Application filed September 2, 1866. Serial No. 212,506. (No model.)

To all whom it may concern.

Be it known that I, WILLIAM B. CROWTHER, Sr., a citizen of the United States, residing at Ocean Beach, in the county of Monmouth and State of New Jersey, have invented a new and useful Improvement in Chimney Cowls and Ventilators, of which the following is a specification.

My invention relates to an improvement in chimney cowls and ventilators; and it consists in the peculiar construction and combination of devices, that will be more fully set forth hereinafter, and particularly pointed out in the claims.

In the drawings, Figure 1 is partly a side elevation of my invention and partly a vertical longitudinal sectional view of the same. Fig. 2 is a vertical section taken on the line α α of Fig. 1. Fig. 3 is a detached perspective view 20 of the spreading cone.

A represents a vertical cylindrical pipe which projects from the upper end of the chimney, and is provided with a vertical pivotal stem, B, which projects above its upper end 25 and at the center of the pipe.

C represents a cowl, comprising a funnel, D, which is arranged horizontally, and a vertical sleeve, E, which depends from the lower side of the funnel D, near the center thereof. The 30 said sleeve is provided near its lower end with a horizontal cross-bar, F, which rests upon the upper edge of the pipe A, and the stem B of the latter passes through an opening which is made in the center of the cross-bar, and has its 35 upper end journaled in the rear end of a funnel, G, which is inserted in the large end of the funnel D, so as to contract the opening in the said latter funnel. By this means it will be readily understood that the cowl is adapted 40 to rotate on the upper end of the pipe A. The rear end of the funnel G projects somewhat beyond the center of the sleeve E, and to the rear end of the said funnel and supported at a slight distance in rear thereof is secured a 45 spreading cone, H, the apex of which is in a line with the longitudinal center of the funnel G. This cone is provided with an opening at its apex, so as to permit the free circulation of air entirely through the cone.

I represents a vane or wing, which is attached to the rear end of the funnel D, on the

upper side thereof, and projects vertically and rearwardly from the said funnel.

The operation of my invention is as follows: The vane serves to keep the mouth of the funnel D, and consequently the mouth of the funnel G is always directed toward the wind, and a current of wind is thus caused to constantly pass through the funnel D and over the chimney. This creates a partial vacuum in the chimney and causes the air to rush upwardly therein, thus preventing the chimney from smoking by insuring active combustion, and also thoroughly ventilating the room in which the fire-place of the chimney is located. The 60 function of the spreading cone is to divert the current of air which passes through the funnel D and the induction-funnel G, and causes it to strike against the sides of the rear portion of the funnel D in a thin spray, and also to give a 70 spiral or cycloidal motion to the current of air, and thus increase the efficiency of the device as a ventilator. The air rushing through the funnel G is partly deflected by the cone H against the sides of funnel D, and partially 75 enters through the cone by means of the opening in the apex thereof. This combined action of the air produces a whirling or cycloidal motion, as will be obvious.

It will be readily understood that the device 80 is not necessarily limited to use on chimneys, as it may be readily employed to ventilate buildings without being placed upon chimneys, the only requisite being that the lower end of the pipe A shall communicate with the 85 apartment which it is desired to ventilate.

The spreading cone H is secured to the funnel by means of rods J, as shown in Fig. 3, that are soldered to the outside of the funnel.

To provide an anti-friction bearing for the 90 stem B, I secure at the top of the cowl a tin piece, T, having guides or ways for a glass block, L, formed with a seat, m, for the upper conical end of the stem.

The cross-bar F, resting on the top of pipe 95 A, supports the sleeve E and funnel D; but to effectually prevent the latter from being blown over, the pivotal rod or stem B passes through the funnel G.

By having the spiral motion to occur at a 100 point away from the center of the sleeve E the smoke arising therefrom cannot be blown down

the chimney, but, on the contrary, the whirling or spiral motion will serve to exhaust or extract the smoke and provide an excellent draft, that will materially assist in making the fire burn.

Having thus fully described my invention, I claim—

1. In combination with the funnel D, the induction-funnel G, extending from one open end of the funnel D, the spreading cone H, having its open end projected into the open inner end of the funnel G, and the rods J, secured to the cone H and adapted to secure the same to the funnel G, as set forth.
2. The combination of the pivoted sleeve or

funnel D, having the vane to direct it to the wind, the induction-funnel G, located in the funnel D, to contract the mouth thereof, and the hollow spreading cone H, located in rear of the funnel G, but out of contact therewith, having its rear side open and provided with an opening in its apex, substantially as described.

In testimony that I claim the foregoing as my own I have hereto affixed my signature in presence of two witnesses.

WILLIAM B. CROWTHER, SR.
